(57) **CLAIM**

The ornamental design for a utility vehicle folding step, as shown and described.

DESCRIPTION

FIG. 1 is a perspective view of a utility vehicle folding step in the down position;

FIG. 2 is a perspective view of another embodiment of the utility vehicle folding step in the down position;

FIG. 3 is a bottom view thereof showing the step in the up position;

FIG. 4 is a top view thereof;

FIG. 5 is a front view thereof showing the step in the up position shown removed from its support bracket for clarity.

FIG. 6 is a back view thereof;

FIG. 7 is a left side view thereof; and,

FIG. 8 is a right side view thereof.

The broken lines in the drawings represent environmental structure and form no part of the claim design.
